(74) Attorney, Agent, or Firm — Tutunjian & Bitetto, P.C.

(57) **CLAIM**

The ornamental design for a rodent trap funnel, as shown and described.

DESCRIPTION

FIG. 1 is a top perspective view of the rodent trap funnel showing my new design;

FIG. 2 is a bottom perspective view thereof;

FIG. 3 is a left side view thereof;

FIG. 4 is rear view thereof;

FIG. 5 is a right side view thereof;

FIG. 6 is a front view thereof;

FIG. 7 is a top view thereof; and,

FIG. 8 is a bottom view thereof.
